UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

SEWING MACHINE.

Application filed September 26, 1925. Serial No. 58,778.

This invention relates to sewing machines of the type having a laterally vibrating needle and adapted to sew a group of stitches and then come to rest; an automatic button-hole sewing machine being an example of the type in question. The invention has for an object to provide a machine of this type having a simplified and improved mechanism for vibrating the needle as well as for 10 periodically changing the amplitude of vibration of the needle, as in barring one or both ends of a buttonhole, which mechanism will operate quietly and smoothly and with certainty and uniformity at high speed and 15 which is under positive control at all times.

Machines of the type in question embody stitch-forming mechanism and a work-holder with feeding mechanism including a feed-wheel and connections for relatively moving 20 the stitch-forming mechanism and work-holder to place the stitches in the desired order in their grouped formation. In the present embodiment of the improvement the feed-wheel is driven through a train of gears, 25 the initial member of such train carrying a star-wheel with which mesh two diametrically opposed pins carried by a gear member driven from the main or needle-bar operating shaft. This pin and star-wheel 30 drive for the feed-wheel imparts to the latter a positive as distinguished from a friction-pawl driven step-by-step rotary motion, with periods of dwell during which the needle passes into and out of the work in the formation 35 of stitches. In the present instance, the needle-bar is mounted in a swinging gate, as usual, but such gate is vibrated by a pitman connection with a rotary crank driven from the feed-wheel actuating mechanism and 40 hence through the pin-and-star-wheel drive. Thus the needle-bar carrying gate is crank-driven instead of cam-driven and is positively tied to the feed-wheel and parts moved thereby, such as the work-holder, and is held 45 stationary with such parts, or work-holder, while the needle passes into and out of the work. Positively acting cam means turning 50 with the feed-wheel operate automatically through suitable connections to shift or increase the eccentricity of the rotary crank and amplify the vibrations of the needle, as when sewing the barring stitches of a buttonhole. The cam-actuated vibration-amplifying mechanism in question is of such a 55 nature that it may be made light in weight

so as to operate efficiently and respond quickly at high speed. The rotary needle-bar vibrating crank is under control at all times during its shift to a position of increased eccentricity and hence the position of the 60 needle-bar gate driven by such crank is fully under control during such shift.

By actuating the needle-bar vibrating mechanism from the intermittent feed-wheel drive, the dwells produced by the feed-wheel 65 drive can also be communicated to the needle-bar guide or gate. A rotary crank-drive can thus be used to advantage, instead of the usual cam-driven arrangements, for vibrating the needle-bar, by timing the crank-drive relative to the feed-wheel drive so that the dwells produced by the latter occur when the crank is in its dead-center or dwell-producing positions. Thus the dwells of the 70 needle-bar guide or gate are practically the 75 sum of the crank-produced dwells (due to the crank rounding its dead-center positions) plus the dwells produced by the intermittent feed-wheel drive.

In the accompanying drawings, Fig. 1 is 80 a side elevation, partly in section, of a buttonhole sewing machine embodying the invention. Fig. 2 is a bottom plan view of the machine. Fig. 3 is a top plan view of the bracket-arm of the machine. Fig. 4 85 is a transverse vertical section through the machine on the line 4—4, Fig. 1. Fig. 5 is a section on the line 5—5, Fig. 4. Fig. 6 is a detail view of an element of Fig. 4. Fig. 7 is a plan view of the cam which controls the amplitude of vibration of the needle-bar. Fig. 8 is a plan view of the variable crank mechanism which vibrates the 90 needle-bar. Fig. 9 is a section on the line 9—9, Fig. 8, and Fig. 10 is a disassembled 95 perspective view of certain parts shown in Figs. 8 and 9.

For the purposes of the present disclosure the invention is described as embodied in an automatic straight buttonhole sewing machine constructed substantially in accordance with the disclosures of the patent to E. B. Allen, No. 1,559,529, issued November 3, 1925, and the copending application of A. R. Wood, Serial No. 27,627, filed 100 May 4, 1925. The machine has the usual bed 1, standard 2, overhanging arm 3 and head 4. The stitch-forming mechanism comprises the reciprocating and laterally vibrat- 105 ing needle-bar 5 carrying the eye-pointed 110

needle 6. The needle-bar 5 is journaled in the swinging gate 7 which is mounted on the pivot pins 8 and derives its vibratory movement from the main sewing shaft 9. 5 The gate 7 may be connected by means of the link 10 to the slotted arm 11 which is fulcrumed at 12 on the bracket-arm 3 and is connected by the link 13 to the crank-pin 14 mounted on the radially movable slide 10 15 carried by the rotary guide-head 16 coaxial with the vertical shaft 17. The guide-head 16 receives semi-rotational impulses through the train of gears 18 from the intermediate feed-actuating shaft 19 which carries the star-wheel 20 with which mesh the pins 21, Fig. 3, carried by the hub of the bevel gear 22 mounted on the bearing pin 23 and receiving its motion from the bevel pinion 24 carried by the sewing shaft 9. The gear 22 is driven at half the speed of the shaft 9 and the gearing 18 is of such ratio that the guide head 16 is given a semi-rotation for each impulse of the star-wheel 20 received from one of the pins 21. The 20 25 needle-bar is reciprocated by means of the usual crank 25 and link connection 26 with the sewing shaft 9.

The shaft 17 is hollow and slidably receives a vertical rod 27 having a taper 30 pointed upper extremity 28 constituting a cam-portion which, when projected upwardly, engages a transverse edge-portion or shoulder 29 carried by the slide 15 and shifts such slide to increase the eccentricity of the 35 crank-pin 14 and thus increase the amplitude of vibration of the needle. The guide-head 16 is equipped with springs 30 which act against shoulders 30', Fig. 10, on the slide 15 to restore it to initial position when the vertical slide-rod 27 is permitted to descend. A stop 15', Fig. 5, secured to one end of the slide 15 is adapted to engage one end of the guide-head 16 and limit the motion of said slide in one direction. 40 45

The vertical slide-rod 27 has fixed to its lower end the lateral pin 31 which is embraced and held against turning about the axis of the rod 17 by the slotted fixed guide 32, Fig. 6, which is secured to the frame 50 of the machine. The pin 31 is also embraced by the forked forward end of the actuating lever 33 which is fulcrumed at 34 on the bracket-arm 3 and has a cam-follower block 35 resting on the upper flat surface of the cam-wheel 36. The cam-wheel 36 is fixed to the same shaft 37 as the main feed-wheel 38 which shifts the work-holder. Secured to the upper surface of the cam-wheel 36 are the raised blocks 39 which engage the block 35 and lift the lever 33 and rod 27 to shift the slide 15 and increase the amplitude of vibration of the needle-bar. In the present machine, the cam-blocks 39 are arranged to increase the vibrations of the needle for 60 65 barring both ends of a straight buttonhole.

The vertical rod 27 within the shaft 17 is positively and forcibly lifted by the cam members 39 on the cam-wheel 36 and, furthermore, is light in weight and adapted to effectively control the amplitude of vibration of the needle under high-speed operating conditions. The needle-gate 7 is connected at all times to the crank 14, the degree of eccentricity of which is under control at all periods of the cycle of operation of the 70 machine. The provision for driving the needle-bar vibrating mechanism from the positively or pin-and-star-wheel gear driven feeding mechanism insures coordination at all times between the movements of the 80 work-holder and the vibrating needle and simplifies the machine by making use of a single intermittent drive mechanism (the pin-and-star-wheel drive) for both moving the feed-wheel intermittently and vibrating 85 the needle.

In the formation of stitches the needle 6 cooperates with the usual shuttle (not shown) which is mounted in the shuttle race 40 and actuated by means of the shuttle-driver 41 on the oscillatory shaft 42 having the usual driving connections with the crank 43 on the main-shaft 9; such connections including the crank-arm 44 and an intermediate rock-lever 45 and pitman 46. 90 95

The work is held by the usual work-clamp comprising the longitudinal slide-plate 47, Fig. 2, on a lateral extension 48 of which is pivotally mounted at 49, Fig. 1, the upper clamp-lever 50 carrying the clamping foot 51. The longitudinal slide-plate 47 is mounted to slide lengthwise of the machine bed in the cross-slide-plate 52 which slides crosswise of the machine bed in the ways 53, 53, Fig. 1. The longitudinal slide-plate 100 is actuated by means of the usual link 54, Fig. 2, and lever 55 having a follower 56 entering the longitudinal feed cam-groove 57 in the feed-wheel 38. The cross-slide-plate is actuated by the lever 58 which is 110 fulcrumed at 59 on the bed 1 and has a follower 60 entering the lateral-feed cam-groove 61 in the feed-wheel. The shaft 37 carrying the feed-wheel 38 and cam-wheel 36 is driven by means of a train of gears 115 62, Fig. 4, from the shaft 19.

The period of action of the stitch-forming mechanism is controlled by the usual stop-motion device comprising the tight and loose pulleys 63, 64, the belt-shipper 65 and the tilting stop-motion lever 66 carrying the vertically movable spring-pressed stop-plunger 67. 120

The particular machine chosen for disclosure of an embodiment of the invention is equipped with a control shaft 68 which is disposed transversely of the machine bed and is actuated from a constantly running power-driven pulley 69 through a suitable 125 partial rotation clutch mechanism including 130

a driven disk 70, Fig. 1, carrying two angularly spaced radially slideable clutch-dogs 71. This mechanism is fully disclosed in the Allen patent, previously referred to and a detailed description thereof is not believed to be necessary to an understanding of the present improvement. It will suffice to explain that this shaft is automatically given a partial rotation prior to the starting of the stitch-forming mechanism and a second partial rotation after the stitch-forming mechanism has come to rest. The first partial rotation of the shaft 68 serves to close the work-clamp and start the stitch-forming mechanism, and the second partial rotation of such shaft is conveniently made use of to operate the button-hole and thread-cutting mechanisms and to open the work-clamp.

Having thus set forth the nature of the invention, what I claim herein is:—

1. In a group-stitching machine, a reciprocating needle, a needle-gate, a crank-shaft, a crank carried by said shaft, a pitman connection between said crank and gate for vibrating the latter, a sewing shaft connected to reciprocate said needle, a work-holder, a feed-wheel connected to impart feeding movement to the work-holder, and means including a pin-and-star-wheel drive actuated by the sewing shaft for imparting step-by-step rotary motion to the feed-wheel, said crank being connected to receive semi-rotational impulses from said pin-and-star-wheel drive.

2. A group-stitching machine having, in combination, a sewing shaft, an intermediate shaft, a pin-and-star-wheel driving connection between said sewing and intermediate shafts for imparting to the latter a step-by-step rotary motion, a crank-shaft geared to said intermediate shaft to receive semi-rotational impulses, a needle-gate connected

to be vibrated by said crank, a reciprocating needle-bar mounted in said needle-gate, a feed-shaft geared to said intermediate shaft to receive step-by-step rotary motion, a feed-wheel actuated by said feed-shaft, and a travelling work-holder actuated by said feed-wheel.

3. In a sewing machine, a frame including a bed and overhanging bracket-arm, a sewing shaft extending lengthwise of the bracket-arm, a needle-gate carried at the free end of the bracket-arm, a vertical shaft journalized in the bracket-arm, a crank on said shaft connected to vibrate said needle-gate, an intermediate vertical shaft journalized in the bracket-arm and geared to said first mentioned vertical shaft, means actuated by the sewing shaft for imparting to said intermediate shaft step-by-step rotary impulses with periods of dwell, a feed-wheel connected to be driven by said intermediate shaft, and a travelling work-holder actuated by said feed-wheel.

4. In a sewing machine, a needle-gate, a needle-bar mounted to reciprocate in said gate, a rotary guide head, a hollow shaft carrying said guide-head, a slide mounted on said guide-head and formed with a transverse shoulder, a crank on said slide connected to vibrate said gate, a slide-rod mounted in said hollow shaft and having a cam portion coacting with said shoulder, spring means on said guide-head acting upon said slide to retain its transverse shoulder in engagement with the cam portion of said slide-rod, and cam means driven by said sewing shaft for periodically shifting said slide-rod to increase the amplitude of vibration of said needle-bar.

In testimony whereof, I have signed my name to this specification.

EDWARD B. ALLEN.
